ATTORNEY

UNITED STATES PATENT OFFICE

105,691

DESIGN FOR A TOY VACUUM SWEEPER OR SIMILAR ARTICLE

Daniel C. Cahalane, Hillsdale, N. J.

Application June 10, 1937, Serial No. 69,769

Term of patent 3½ years

To all whom it may concern:

Be it known that Daniel C. Cahalane, a citizen of the United States and resident of Hillsdale, in the county of Bergen and State of New Jersey, has invented a new, original and ornamental Design for a Toy Vacuum Sweeper or Similar Article, of which the following is a specification, reference being had to the accompanying drawing, forming part thereof, in which the figure is a perspective view of a toy vacuum sweeper embodying my new design.

I claim:

The ornamental design for a toy vacuum sweeper or similar article, as shown.

DANIEL C. CAHALANE.
